UNITED STATES PATENT OFFICE

2,595,551

FEEDING DEVICE FOR RIVETS OR SIMILAR ARTICLES

Maurice Stanley Springate, Oaklands, England, assignor to Aviation Developments Limited, Welwyn Garden City, Herts, England, an English joint-stock company

Application May 18, 1948, Serial No. 27,621
In Great Britain May 23, 1947

3 Claims. (Cl. 218—19)

1

This invention relates to feeding devices of a magazine type for small articles such as solid or tubular rivets, sealing pins and the like which are urged in steps within the magazine to pass one at a time between jaws at the end of the magazine. Although not exclusively limited thereto the invention is of a special use for magazine type riveting gun of the kind in which rivets are threaded over the stem of the mandrel having an enlarged, e. g. pear-shaped head which is pulled through each rivet in succession in order to fix it in position by expanding the tail of the rivet, whilst the jaws are acting as an anvil against which the rivet bears as it is expanded.

In such known feeding devices, the jaws are opened by co-operation, cam fashion, with internal projections located at the outer ends of the jaws of the head of the emerging rivet or the like, as it is advanced.

According to the invention, a feeding device for rivets and the like, includes a tubular housing, at least two jaws protruding out of the forward end of the housing, each jaw being formed, at its protruding end with an internal lip and intermediate of its length with an external projection, and spring means serving to urge the jaws into the housing so as normally to hold the external projections on the jaws in contact with the forward end of the housing, so that the jaws are in their closed positions.

Preferably, the feeding device includes an internal flange formed at the forward end of the housing, an external flange formed at the rear end of each jaw, and a compression spring located between the said internal and external flanges serving to urge the jaws into the housing and normally to hold the external projections against the internal flange on the end of the housing.

A preferred form of the invention will now be described with reference to the accompanying drawings in which:

Fig. 1 is an external view of one form of the feeding device;

Fig. 2 is an end view looking at the lower end of Figure 1 in the direction of the arrow A;

Fig. 3 is an end view looking at the upper end of Figure 1 in the direction of the arrow B;

Fig. 4 is a sectional side elevation through the feeding device showing the jaws in closed position;

Fig. 5 is a similar view to that of Fig. 4 illustrating the jaws in open position;

Fig. 6 is an external view of a modified form

2

of the feeding device according to the invention.

As illustrated, the feeding device comprises two split or diametrically opposed jaws 1 and 2 which are formed at their protruding or outer ends with internal lips 3 and intermediate of their lengths with shaped external projections 4 which are of progressively decreasing radial height or depth towards the inner ends of the jaws 1, 2. At their inner ends, the jaws are formed with an external flange 5. To facilitate the assembly of the jaws 1, 2, their shaped external projections 4 have flats 6 at opposite sides. The jaws 1 and 2 present between them a cylindrical passage 7 of such a diameter that the enlarged heads of the rivets 8 are an easy running fit in the passage 7. This passage or bore 7 is chamfered at its inner end 9 to facilitate the entrance of the advancing rivet 8 or similar article. At the outer or protruding end, the bore 7 of the jaws 1, 2, is constricted in diameter at 10 corresponding to that of the shank of the rivet 8 or similar article, the larger and smaller diameter bores 7 and 10 respectively being connected by inclined surfaces 11 which ride on the edge of the emerging rivet head 8.

The jaws 1, 2, are located in a tubular housing 12, adapted to be screwed on or otherwise secured to the barrel 13 of a riveting tool or gun, not shown. The jaw housing 12 has a cap 12a threaded on its forward end and this cap is provided with an internal flange 14 at its outer end formed with an outwardly opening internal taper 15. A coiled compression spring 16 is disposed within the jaw housing 12 around the jaw members 1, 2. The compression spring 16 abuts at one end against the inner face of the internal flange 14 of the jaw housing 12 and at the other end against the external flange 5 of the jaws 1, 2. The jaws may be inserted in the housing by first assembling the two jaws with the spring 16 surrounding them. The small ends of the jaws are then inserted into the cap 12a from the threaded side of the cap, before the cap is applied to the housing, and by displacing one jaw axially with respect to the other, the external projections 4 on the two jaws will pass through the opening in the cap 12a at separate times, and upon release of the two jaws spring 16 will cause them to seat properly on the tapered face 15 of flange 14 as shown in Figure 1.

The arrangement is such that the spring 16 urges the jaws 1, 2, into their rearward, closed position in which the tapered surfaces of their external projections 4 and the tapered surface

15 of internal flange on the jaw housing 12 contact to prevent the jaws 1, 2 from moving apart.

When the riveting gun is in operation, on the feed stroke the leading rivet 8 is pushed forward by the gun mechanism, not shown, the rivets being moved tail first along a mandrel 19 as in the case of a blind riveting appliance, within the internal bore 7 of the jaws 1 and 2, and the edge of the head of the leading rivet 8 engages the inclined surfaces 11 formed at the outer or protruding ends of the jaws 1, 2. As the force imparted to the advancing rivet 8 is greater than that of the coiled compression spring 16 acting on the jaws 1, 2, such rivet 8, as it advances, shifts the jaws 1, 2 axially forwardly, against the influence of spring 16 and parts them radially to permit the rivet 8 to pass axially therethrough and into contact with the enlarged head 18 of the mandrel. When the leading rivet 8 has cleared the jaws 1, 2, the latter are returned by 20 the coil compression spring 16 to their closed positions and thereafter the front face 17 of the jaws 1, 2, acts as an anvil.

Upon the termination of the working stroke and during succeeding feeding stroke the jaws 1, 2 are again displaced by the next leading rivet 8 against spring influence.

The jaws 1, 2 may be made in various sizes and in a modified form of the invention as illustrated in Fig. 6 they may be curved so as to allow the operator to perform riveting operations in places which are difficult of access.

The improved jaws offer advantages both from the operational and from the manufacturing point of view. For example, when the jaws 1, 2 are used in connection with blind riveting appliances, in which a tubular rivet 8 is expanded by the withdrawal of the head 18 of the mandrel 19 therethrough, the locking action will be the greater, the greater the load applied axially. Moreover, the closing of the jaws 1, 2 after a rivet 8 has passed therethrough is assured and the jaws 1, 2 are automatically restored to, and locked in their closed position by this action which may be repeated immediately so that the riveting operation may be carried out without any interruption.

The jaw mechanism is very simple and has a minimum of parts.

What I claim is:

1. A feeding device for rivets and the like, including a housing, at least two jaws protruding out of the forward end of the housing, each jaw being formed at its protruding end with an internal lip provided with a tapered inner surface and intermediate its length with an external projection, and spring means comprising a helical spring located within said housing and acting 10 against surfaces of said housing and said jaws in a direction to urge the jaws into the housing so as normally to hold the external projections on the jaws in contact with the forward end of the housing, the contact surface of at least one of said contacting parts being tapered in a direction to urge the jaws towards their closed position.

2. A feeding device according to claim 1 in which the housing has an internal flange formed at the forward end, and the jaws each have an external flange at the rear end, said helical spring comprising a compression spring surrounding said jaws in the space between said internal and external flanges whereby the jaws are urged into the housing and normally hold the external projections against the internal flange at the forward end of the housing.

3. A feeding device according to claim 1 in which the contour of the contacting surfaces of the external projections and the forward end of the housing are such as to permit relative movement under the action of said spring of the jaws and housing into a final position of retraction of the jaws within the housing from which the jaws may not be opened without first being moved at least partly out of the housing.

MAURICE STANLEY SPRINGATE.
